UNITED STATES PATENT OFFICE.

ALPHONSO T. PALMER, OF CHICAGO, ILLINOIS.

RAIL CLAMP.

Application filed May 24, 1926. Serial No. 111,141.

This invention relates to rail clamps or anti-creep devices for preventing longitudinal movement of railway rails, and has for its object the provision of a device of the class 5 named which shall be simple in construction, easy to apply, and efficient in operation, and which shall clamp the rail with a powerful grip.

Other objects of the invention will appear 10 hereinafter.

The invention is exemplified in the combination and arrangement of parts shown in the accompanying drawing and described in the following specification, and it is more 15 particularly pointed out in the appended claims.

In the drawing,

Fig. 1 is an elevation of a rail clamp applied to the supporting flange of a rail.

20 Fig. 2 is a top plan view of the device shown in Fig. 1.

Fig. 3 is an elevation of the clamp.

The numeral 10 designates a railway rail, supported on a cross tie 11 in the usual manner. The rail clamp comprises a yoke 12 having hooks 13 and 14 at the opposite ends thereof for engaging the opposite edges of the bottom flange 15 of the railway rail. The hook 13 is provided with a recess 16, 25 which may be placed over one edge of the flange 15 with the clamp in the position shown in broken lines in Fig. 1. The hook 14 may then be raised to bring the notch 17 therein into registration with the edge of the flange 15. The clamp is then moved to the 30 right as viewed in Fig. 1 to bring the edge of the flange 15 into the notch 17, as shown in full lines in Fig. 1. This will bring the opposite edge of the flange out of the recess 16

35 and permit the engaging face 18 of the hook 13 to rest upon the upper face of the flange 15. The upper edge 19 of the yoke 12 will then be in the inclined position shown in full lines in Fig. 1. The body of the clamp is 40 provided with a longitudinal slideway 20 for receiving a wedge 21. This slideway is open at its top throughout the yoke portion 12 of the clamp but is in the form of a closed loop surrounding the wedge 21 at each end of 45 the clamp. When the clamp has been placed in the position shown in Fig. 1 it is moved into contact with the side of the tie 11, and the wedge 21 is then driven into the slideway 20 until it tightly wedges the clamp to the 50 flange 15. The opposite edges of the wedge 55 may be provided with notches 22 to facilitate

driving the wedge into position and to assist in preventing displacement of the wedge after it has been driven home. In driving the wedge into its slideway a suitable driving 60 plug will be inserted into the opening in the end of the clamp and in contact with the end 23 of the wedge 21. Since the end of the wedge is enclosed within the opening 20 and does not project beyond the end of the clamp, 65 it will not be possible to batter the end of the wedge by the blows used to drive it into position. It will be seen that the wedge is tapered slightly so that it is thinner at its lower edge than at its upper edge. The 70 wedge fits tightly between the walls of the slideway 20 so that as the top edge of the wedge contacts with the lower face of the flange 15 the wedge will be moved downwardly, leaving a slight space indicated at 75 24 between the top of the wedge and the top face of the guide opening. This forces the wedge tightly between the side walls of the guide opening so that the walls will grip the wedge 80 with sufficient force to prevent the wedge from working loose.

When it is desired to remove the clamp, a driving tool will be inserted through the small end of the guide opening at the left in Fig. 1 and the wedge driven backwardly until 85 the clamp is released. Lugs 25 project laterally at each side of the hook 13 and against the top face of flange 15. This braces the clamp against any tendency to tilt or rock about its axis and so prevents the 90 clamp from working loose from the rail flange.

If desired, the clamp may be held tightly against the face of the tie 11 by means of wood screws 26, the heads 27 of which engage 95 the ends of the clamp and draw the clamp against the face of the tie. In this way the rail is clamped to the tie against longitudinal movement in both directions. Where it is only necessary to hold the rail against movement in one direction the screws 26 may be dispensed with, and even where it is desirable to clamp the rail against movement in both directions, this may be done without using the screws 26 by placing clamps at 100 both sides of the tie.

It will be seen in Fig. 3 that the wedge 21 is symmetrically placed relative to the clamp so that the stress produced by the wedge is 110 equally divided between the opposite sides of the clamping member. This prevents any inequality of stress which might tend to tilt

or cant the clamp. It also insures economical distribution of the material of the clamp since the stress is equally distributed between the opposite sides of the clamp. The parts of the clamp which withstand the stress are placed in direct tension and there is no bending movement due to unsymmetrical arrangement of the parts.

In the manufacture of railway rails, there is likely to be a slight variation in the width and thickness of the lower flange. A slight variation in this respect is permitted by the railroads, and it is necessary that a rail clamp, to be successful, must adapt itself to this variation and be capable of clamping the rail for either extreme of variation allowed. In the present invention, the variation in the width of the flange does not interfere with the clamping action since the hooks do not engage the edges but contact with the top inclined portions of the flange. The variation in thickness is taken up by the wedging action. It will be apparent that when the wedge is driven home, it will clamp the flange between the top edge of the wedge and the engaging faces of the hooks irrespective of the variations in the thickness of the flange.

I claim:

1. A railway clamp comprising a yoke extending beneath the bottom flange of the rail from one side to the other thereof, inwardly extending hooks disposed at opposite ends of said yoke for engaging the top face of the rail flange, and a wedge for forcing said yoke downwardly to tighten said hooks upon the upper face of the rail flange said wedge having transversely extending grooves and ridges substantially throughout its length to hold said wedge from longitudinal and lateral displacement.

2. A rail clamp comprising a yoke having hooks at opposite ends thereof for engaging the top faces of the opposite edges of a rail flange, said clamp having a tapered guideway therein, and a wedge arranged to be driven into said guideway with its top surface in contact with the bottom face of the rail flange to draw said hooks into tight engagement with the rail flange said wedge having transverse grooves and flat topped ridges in the upper face thereof for engaging the bottom face of the lateral flange.

3. A rail clamp comprising a yoke extending beneath a railway rail and having hooks at opposite ends thereof for engaging the top face of the bottom flange of the rail at opposite edges thereof, said clamp having a longitudinally extending guideway disposed centrally thereof, and a wedge arranged to be driven into said guideway to clamp said hooks against the top face of the rail flange said wedge and guideway being tapered in width from top to bottom thereof and having substantially flat lateral faces.

4. A rail clamp comprising a yoke extend-

ing beneath a railway rail and having upwardly and inwardly extending hooks at opposite ends thereof for engaging the top surface of the opposite edges of the rail flange, and a wedge for clamping the hooks against said rail flange, said yoke having a longitudinally extending guideway therein positioned to receive said wedge in symmetrical relation with the central longitudinal vertical plane of said clamp said wedge and guideway being tapered in width from top to bottom thereof, said wedge having spaced flat contact surfaces on the upper side thereof.

5. A railway clamp comprising a yoke having hooks thereon for engaging the rail, and a wedge for holding said hooks in contact with said rail, said clamp having a tapered guideway therein for receiving said wedge, the side walls of said guideway being substantially flat and inclined toward each other downwardly so that said wedge is forced tightly between said side walls by the pressure on the upper face thereof when driven into position.

6. A rail clamp comprising a yoke having hooks thereon for engaging a railway rail, a wedge for clamping said hooks against said rail, said wedge having substantially flat side faces and being tapered in cross section so that transverse force on said wedge will tighten said wedge in its guideway.

7. A rail clamp comprising a yoke disposed beneath a railway rail and extending transversely thereof, said yoke having hooks at opposite ends thereof for engaging the top faces of the opposite edges of the rail flange, said yoke having a guideway extending longitudinally thereof, a wedge having its upper and lower faces inclined from end to end relative to each other and movable into said guideway for clamping said hooks against the rail flange, the lateral faces of said wedge being substantially flat and inclined inwardly and downwardly while the walls of said guideway are correspondingly inclined so that the force exerted upon the top edge of said wedge will tighten said wedge between the walls of said guideway, thus producing a clamping action for preventing displacement of said wedge.

8. A railway rail comprising a yoke having hooks at opposite ends thereof for engaging the flange of a rail, and a wedge for clamping said hooks against said flange, said wedge having transverse indentations on the active face thereof to provide spaced flat contact faces for preventing slippage of said wedge in its guideway and movement of said clamp on the rail.

9. A rail clamp comprising a yoke having hooks at opposite ends thereof for engaging the opposite edges of a rail flange, said yoke having an interior guideway therein for receiving a wedge, and a wedge arranged to be driven in said guideway, said wedge

being shorter than said guideway so that the ends of said wedge will be protected by the sides of said guideway.

10. A rail clamp comprising a yoke having a hook therein for engaging a railway rail, and laterally projecting lugs on said hook for preventing canting of said clamp.

11. A rail clamp comprising a yoke having hooks thereon for engaging a rail, a wedge for clamping said hooks upon said rail, and fastening devices for engaging a tie to hold said clamp against the lateral face of said tie.

12. A rail clamp comprising a yoke having upwardly and inwardly projecting hooks at opposite ends thereof for engaging the bottom flange of a rail, said hooks being spaced apart at their bases a distance greater than the width of a rail flange, one of said hooks having its engaging face spaced upwardly from said yoke a distance greater than the thickness of said flange, said yoke having a tapered guideway therethrough having its larger end adjacent said last mentioned hook, and laterally projecting lugs having contact faces disposed on the same plane as the contact face of said hook.

13. A rail clamp comprising a yoke arranged to extend beneath a rail, hooks projecting upwardly and inwardly at opposite ends of said yoke, said hooks being spaced apart at their bases an amount greater than the width of the bottom flange of said rail, one of said hooks having a wider opening than the other to permit vertical movement of said rail clamp at one end thereof, said yoke having a longitudinally tapered opening therethrough, a wedge arranged to be driven into said opening and held thereby in symmetrical relation to the longitudinal vertical central plane of said yoke, the side walls

of said guideway and the sides of said wedge being tapered inwardly and downwardly, and laterally projecting bracing lugs on one of said hooks for preventing lateral canting of said clamp.

14. A rail clamp having contact members arranged to engage the top inclined faces of the lower flange of a railway rail leaving the edges of the flange free from clamping engagement to permit tolerance in the width of the flange and wedging means arranged to engage said rail to draw said contact members tightly against said inclined faces.

15. A rail clamp comprising a yoke having spaced contact members thereon for engaging the top face of the bottom flange of a railway rail, said contact members being spaced on said yoke a distance greater than the width of said bottom flange and a wedging device for clamping said contact members against said flange irrespective of variations in the thickness of said flange.

16. A rail clamp comprising a yoke arranged to extend beneath the bottom of a rail flange, said yoke having hooks at opposite ends thereof provided with inclined contact faces for engaging the inclined upper surface of the rail flange, said hooks being spaced apart a greater distance than the width of said flange to permit slight variations in said width, and a wedge for contacting with the lower face of said flange for forcing said flange into gripping engagement with the inclined contact faces of said hooks irrespective of slight variations in the thickness of said flange.

In testimony whereof I have signed my name to this specification on this 21st day of May, A. D. 1926.

ALPHONSO T. PALMER.
